UNITED STATES PATENT OFFICE.

EUGENE FULLER, OF PROVIDENCE, RHODE ISLAND.

DESIGN FOR A LACING-TIP.

55,375.

Specification for Design.

Patented June 1, 1920.

Application filed January 19, 1920. Serial No. 352,625. Term of patent 14 years.

To all whom it may concern:

Be it known that I, EUGENE FULLER, a citizen of the United States, residing at the city of Providence, county of Providence, State of Rhode Island, have invented a new, original, and ornamental Design for a Lacing-Tip, of which the following is a specification, reference being had to the accompanying drawing, forming part thereof.

The figure is a perspective view of a lacing tip, illustrating my new design.

I claim:

The ornamental design for a lacing tip, as shown.

EUGENE FULLER.
